UNITED STATES PATENT OFFICE.

FORREST NAGLER, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

HYDRAULIC MACHINE.

Application filed July 11, 1921. Serial No. 483,933.

To all whom it may concern:

Be it known that FORREST NAGLER, a citizen of the United States, residing at Wauwatosa, in the county of Milwaukee and State of Wisconsin, has invented a certain new and useful Improvement in Hydraulic Machines, of which the following is a specification.

This invention relates in general to improvements in the art of hydraulics, and relates more specifically to improvements in the construction and operation of direct connected rotary hydraulic machines such as pumps and turbines.

An object of the invention is to provide a hydraulic machine which is simple in construction and efficient in operation. Another object is to provide for proper alignment of the elements of direct connected hydraulic machines, either of the type wherein a prime mover is employed to drive a pump, or of the type wherein a hydraulically actuated element drives an energy absorber. A further object is to provide an improved structure which serves the dual function of supporting elements of a hydraulic machine and of conducting liquid. Still another object is to provide an exceedingly simple and compact hydraulic unit which is especially adapted for installation in places where the available space is limited. These and other objects and advantages of the invention will be apparent from the following description.

A clear conception of an embodiment of the invention and of the operation of a device constructed in accordance therewith, may be had by referring to the drawing accompanying and forming a part of this specification in which like reference characters designate the same or similar parts in the various views.

Fig. 1 is a part sectional side elevation of a motor driven pump unit, the section being taken centrally through the pump and the conduits leading to and from the same.

Fig. 2 is a top view of the motor supporting element and pump, the motor having been omitted.

Fig. 3 is a fragmentary central vertical section through another form of pump.

While the invention is illustrated and described herein as applied specifically to an electric motor driven rotary pump, it will

be apparent that the principles are readily applicable to any hydraulic machine where-
in an hydraulic impeller is associated with
an energy absorber. The unit specifically
illustrated in Figs. 1 and 2, comprises in gen-
eral an electric motor 2, an axial flow pump
impeller 3 direct connected to the motor 2
by means of a horizontal main shaft 4, a
combined base and suction passage forming
element 5, a horizontal inlet pipe 6, communi-
cating with the suction passage of the ele-
ment 5, and a horizontal discharge pipe 8
likewise communicating with the passage in
the base 5. The electric motor 2 is provided
with lower supporting feet which rest upon
and are secured to upper pads 13 formed
integral with the base element 5. The base
element 5 is provided with depending lower
pads or feet 14 which form supports for both
the motor 2 and the pump. The base ele-
ment 5 is further provided with conduit
portions or passages 10, 11, the former of
which is located directly below the motor 2
and communicates directly with the inlet
pipe 6, and the latter of which is inclined
and connects the passage 10 with the inlet
side of the pump impeller 3 on the side of
the impeller facing the motor 2. The dis-
charge pipe 8 forms a horizontal discharge
conduit 12 communicating axially with the
impeller 3 and with the passage 11 formed
in the base element 5. Between the base
element 5 and the discharge pipe 8 is located
a bearing support 7 having fluid guiding
vanes 9 extending inwardly through the dis-
charge conduit 12 and supporting a central
bearing for the shaft 4 located closely ad-
jacent to the impeller 3. The shaft 4 pen-
etrates a boss 15 formed on the base 5, and
may be provided with a stuffing box in this
boss.

In the installation illustrated in Fig. 3, the inclined suction passage 22 formed in the base element 16 is directed axially toward the impeller 12 on the side thereof facing the driving motor, not shown, which may be similar to that disclosed in Fig. 1. The horizontal discharge pipe 18 has a tapered con-
duit 23 therein which likewise communicates axially with the impeller 20. The bearing supporting element 17 is located between the base element 16 and the pipe 18 in advance 100
105 of the impeller 20 and has bearing support-

ing guide vanes 19 which are formed to properly guide the water toward the impeller 20. The main shaft 21 penetrates a boss 24 of the base element 16 and may also 5 be provided with a suitable stuffing box at the boss.

During normal operation of the installation illustrated in Figs. 1 and 2, the operation of the motor 2 produces rotation of the 10 shaft 4 and of the impeller 3, causing the impeller to draw liquid from the inlet pipe 6 through the passages 10, 11 and to deliver the liquid past the guide vanes 9 and into the discharge conduit 12. The formation 15 of the guide vanes 9 is such that the whirling liquid delivered from the impeller 3 is caused to flow axially into the conduit 12, such delivery being desirable in order to reduce to a minimum the hydraulic friction 20 losses induced by the advancing fluid. The delivery of the liquid axially to the impeller 3 and the axial discharge therefrom, further reduces the hydraulic losses. The friction losses are further reduced by entirely 25 avoiding abrupt turns in the course of the liquid, thereby producing a unit of maximum efficiency. By associating both the motor 2 and the impeller 3 with a common base element 5, perfect alinement of the driving 30 and driven members is positively assured. The entire unit is exceedingly compact thereby enabling its installation where the available space for such installation is limited.

The operation of the unit disclosed in 35 Fig. 3 is similar to that disclosed in Figs. 1 and 2, differing only in that the guide vanes 19 serve to admit the liquid to the impeller 20 with whirling components. The gradually tapering discharge conduit 23 40 serves as a diffuser for effectively converting the velocity energy of the discharged liquid into pressure.

It will be obvious that either of the units 45 illustrated may readily be employed as a turbine unit by admitting the liquid through the conduit 12, 23, from a suitable source adapted to produce static pressure, and by substituting a suitable energy absorber for the driving element or motor 2. The passages 10, 11 are formed to effect diffusion 50 of the fluid discharged from the turbine impeller and the turbine unit thus produced would be exceedingly simple, compact and efficient.

55 It should be understood that it is not desired to limit the invention to the exact details of construction and of operation herein shown and described, for various

modifications within the scope of the claims 60 may occur to persons skilled in the art.

It is claimed and desired to secure by Letters Patent:

1. In combination, a bladed rotor, an energy translating device having a rotor 65 direct connected with said bladed rotor, and a single casing providing a direct support for said device and for said bladed rotor and forming a conduit communicating with said bladed rotor, said casing conduit having a portion extending in line with the axis 70 of said rotors, another portion parallel to said axis, and another portion connecting said axial and parallel portions and forming an oblique angle with said axis.

2. In combination, a bladed rotor, an 75 energy translating device having a rotor direct connected with said bladed rotor, and a single casing providing a direct support for said device and for said bladed rotor and forming a conduit communicating with 80 said bladed rotor, said casing conduit having a portion below said device which is laterally widened and vertically narrowed.

3. In combination, a bladed rotor, an 85 energy translating device having a rotor direct connected with said bladed rotor, and a single casing providing a direct support for said device and for said bladed rotor, said casing forming a conduit extending below said device and communicating with 90 the side of said bladed rotor facing said device, said conduit having a circular cross sectional area adjacent to said bladed rotor and being laterally widened and vertically narrowed below said device.

4. In combination, a bladed rotor, an 95 energy translating device having a rotor direct connected with said bladed rotor, and a single casing providing a direct support for said device and for said bladed 100 rotor, said casing forming a conduit comprising a portion located below said device and extending parallel to the axis of said rotor, another portion extending in line with said axis, and another portion connecting said axial and parallel portions and forming an oblique angle with 105 said axis, the portion of said conduit extending in line with said axis being circular in cross section and the portion of said conduit located below said device being laterally widened and vertically narrowed.

In testimony whereof, the signature of the inventor is affixed hereto.

FORREST NAGLER.
